UNITED STATES PATENT OFFICE.

CHARLES A. NELSON, OF UTICA, NEW YORK, ASSIGNOR TO SAVAGE ARMS CORPORATION, A CORPORATION OF DELAWARE.

FIREARM.

1,239,124.

Specification of Letters Patent. Patented Sept. 4, 1917.

Application filed May 15, 1917. Serial No. 168,636.

To all whom it may concern:

Be it known that I, CHARLES A. NELSON, a citizen of the United States, residing at Utica, in the county of Oneida and State of New York, have invented certain new and useful Improvements in Firearms, of which the following is a specification.

This invention relates to firearms of the class in which the firing mechanism includes a longitudinally movable striker or equivalent firing means and a firing means dogging member movable in a fixed part of the arm into and out of dogging relation to said firing means, and it consists in a simple, reliable and conveniently manipulated means for adjusting the dogging member relatively to the firing means so as to require more or less movement of said member, as desired, in order to release the firing means.

20 In the drawing,

Figure 1 is a fragmentary side elevation of a gun of the class indicated having the part thereof with which my invention is immediately concerned in section;

25 Fig. 2 is a top plan view of the part of the gun shown in Fig. 1; and

Fig. 3 is a transverse sectional view on line 3—3, Fig. 1.

20 *a* is the barrel having a rearward extension *b* forming the breech-casing, which contains the longitudinally movable breech-bolt formed in two sections, to wit, the rear rotary section *c'*, having a handle (not shown) received by the rearwardly open annular slot *d* in the breech-casing, and the forward section *c''*, which is held against turning by suitable engagement with the breech-casing. The breech-bolt may be removed from the gun in the usual manner, to wit, 35 by rearward withdrawal when the handle thereof has been brought into the longitudinal part of slot *d*.

30 *e* is the striker arranged in the breech-bolt and normally held forward by a spring *f*; at *g* it has a cocking shoulder to be engaged by the dogging member.

35 At the under side the breech-casing has an opening *h* and registering with said opening, when the breech-bolt is forward, breech-bolt section *c'* has an opening *i*.

The dogging member in the present in-

stance is formed as one piece with the trigger, being a bell-crank lever *j* fulcrumed in the breech-casing at *k* and having a forwardly extending arm *l* equipped with an 55 upwardly dog *m* and a downwardly extending arm *o* suitably shaped to form the trigger. Bearing against the under side of the arm *l* is a spring-pressed plug *p* housed in a cup *q* inset in the stock *r* of the arm. 60 The dog *m*, extending through the opening *h*, is held by the spring-pressed plug *p* bearing against the under side of the striker, being accommodated by the breech-bolt opening *i* so as not to interfere with the longitudinal 65 and rotary movement of its section *c'*, and adapted to dog the striker at *g* in the cocking of the piece.

70 In the forward arm *l* of the lever *j* is tapped an adjusting screw *s* whose head, when the piece is cocked, bears against the under side of the breech-casing in registry with a hole *t* therein at a point where, upon removal of the breech-bolt, said hole, and hence the head of the screw *s*, will be accessible through slot *d* to a screw-driver or other implement for turning the screw.

75 Upon turning the screw the bell-crank lever *j* will be obviously shifted on its fulcrum so as to require more or less movement 80 thereof in order to cause the dog *m* to clear the cocking shoulder *g*.

Having thus fully described my invention, what I claim as new and desire to secure by Letters Patent is:—

85 In combination, with a fixed breech-casing—including part of a gun, a breech-bolt arranged therein, firing mechanism including a longitudinally movable firing means housed in the breech-bolt and a firing means dogging member movable in said fixed part into and out of dogging relation to said means, and an adjusting screw tapped in said member and having a head abuttable against the breech-casing exteriorly thereof, 90 said breech-casing having a hole registering with the screw-head and means affording access to said hole, on removal of the breech-bolt, to an implement for adjusting said screw. 95

100 In testimony whereof I affix my signature.

CHARLES A. NELSON.
